(57) CLAIM

The ornamental design for an aromatherapy shower tablet dissolver, as shown and described.

DESCRIPTION

FIG. 1 is a top-front-left side perspective view of an aromatherapy shower tablet dissolver, showing our new design;

FIG. 2 is a front elevational view thereof;

FIG. 3 is a back elevational view thereof;

FIG. 4 is a left side elevational view thereof, the right side elevational view being a mirror image thereof;

FIG. 5 is a top plan view thereof; and,

FIG. 6 is a bottom plan view thereof.

The broken lines in the drawings depict unclaimed subject matter and form no part of the claimed design.

1 Claim, 5 Drawing Sheets
